UNITED STATES PATENT OFFICE

WILLIAM HAZEL ADAMS, OF BELLAIRE, OHIO.

MOLD-STRIPPER.

SPECIFICATION forming part of Letters Patent No. 393,199, dated November 20, 1888.

Application filed August 30, 1888. Serial No. 284,168. (No model.)

To all whom it may concern:

Be it known that I, WILLIAM HAZEL ADAMS, a citizen of the United States of America, residing at Bellaire, in the county of Belmont and State of Ohio, have invented certain new and useful Improvements in Mold-Strippers; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this specification.

15 My invention relates to improvements in mold-stripers; and it consists in the novel construction and combination of the parts, as will be more fully hereinafter described and claimed.

20 The object of my invention is to save labor, time, and avoid danger to life in stripping cast ingots from molds by an apparatus which is simple and effective in its construction and operation, strong and durable, and easily handled and readily understood. I attain this object by the construction of device illustrated in the accompanying drawings, wherein like letters of reference are used to indicate similar parts in the several views, and in which—

25 Figure 1 represents a molding-plant in side elevation, showing my improved stripper used in connection therewith. Fig. 2 is a side elevation of the stripper. Fig. 3 is a horizontal section thereof on the line $x-x$ of Fig. 2. Fig. 30 4 is an enlarged view of the stripper in section, showing the two positions of the stripper-arms and plunger in dotted and full lines.

35 A indicates a hydraulic crane, on the arm B of which a truck, C, is mounted, having a depending hook, c.

40 M represents the mold, having ears m, all of which are well known in the art.

The stripper consists of a cylindrical casing, D, with a vertical passage therethrough, and 45 lateral openings d in the upper part thereof, extending into the said central vertical passage or opening in said casing, the lower walls of which are downwardly inclined, as shown in Fig. 4. The lower part of the casing D has 50 ears G, formed integral therewith, and diametrically-situated bars or rods g running trans-

versely across and through said ears. The upper hooked end of a gravity-catch, H, is placed over each of the rods g, the lower enlarged shoulder end depending to within a short distance of the lower edge of the casing D and adapted to fasten to the ears m of the mold M. 55

Within the casing D a plunger, E, is movably mounted. The lower end of the said plunger is flared, as at e², and fits in a corresponding recess in the bottom of the casing D, to thereby allow it to be forced below the lower edge of the casing. The upper part of the said plunger is constructed with a transverse slot, e, extending therethrough, having a lower A-shaped wall, e'. 60

Within the slots or openings d of the casing D the enlarged circular ends f² of lever-arms F are eccentrically mounted by means of pivot-pins f¹ passing through the casing, as shown 70 in Figs. 2, 3, and 4. The said enlarged ends f² of the levers F bear upon the two inclined surfaces of the lower wall, e', of slot e of the plunger and are allowed to have movement through said slot e. The lever-arms F are 75 slightly curved outward and inward from the inner enlarged ends, f², to plain or short straight surfaces f on the one edge thereof, and from thence the inner opposing edges, as shown in Figs. 2 and 4, are straight and extend outward away from each other, the outside edges being slightly curved. When the two lever-arms F are together, as shown in Figs. 1 and 4, the two surfaces f bear against each other, and a V-shaped space is formed above the 80

same by the inner outwardly-inclined straight edges of said lever-arms. The free ends of the lever-arms are formed with apertures f', in which the lower ends of chains or cables w² are secured, the upper ends of said chains or cables w² being attached to a ring, w', to which the lower end of a chain or cable, w, depending from the hook c of the truck C, is also fastened. Depending from the ring w', between the chains or cables w², is a similar chain 95 or cable, w³, carrying a yoke, w⁴, at its lower end, which is attached to the upper end of a suspended wedge-block, W.

As shown in Figs. 3 and 4, the enlarged eccentrically-mounted ends f² of the lever-arms 100 F do not work against but slide past each other. This arrangement is made in order to provide

the greatest amount of working-surface in the most compact form. To aid in the attainment of this operation, the said ends f^2 are constructed of less thickness than the remaining 5 part of the lever-arms, a shoulder, f^3 , being formed adjacent to said ends on reverse sides of each of the said arms, as shown in full and dotted lines, Figs. 3 and 4.

To aid in guiding the casing D and the parts 10 carried thereby over the mold M, a chain or cable, y , is attached to one side thereof, as shown in Fig. 1.

In operation the stripper is swung over 15 the mold M, as shown in Fig. 1. The arm B of the crane is lowered until the plunger rests on the ingot, thus slackening the chains w and w^2 . The arms F slightly open, drawing the plunger E up into the casing D sufficiently to have the hooks H strike the ears 20 m of mold M and engage therewith and hold the stripper down on the mold. When the chain w is slackened by lowering the crane-arm B and allowing the plunger to rest on the ingot, as hereinbefore set forth, the wedge-block 25 W by its own weight or gravity drops down in the angle of the V, formed by the inner opposing edges of the arms F, and the said arms are thus assisted in their desired separation. The lower end of the plunger 30 will now be situated directly over and in alignment with the opening in the upper end of the mold. By raising the arm B of crane the arms F of the stripper are drawn together and the plunger E is forced down against the casting and pushes it out of the lower end of 35 the mold. The ingot remains in the pit, to be subsequently removed, and the mold is carried to a convenient place. The arm B of the derrick is then lowered again and the hook 40 H released from the ears m of the mold. The stripper is then ready to be used in a similar manner with another mold.

The utility of my invention is readily appreciable to those skilled in the art, and it is unnecessary to further enlarge upon the same 45 herein.

Having thus described my invention, what I claim as new, and desire to secure by Letters Patent, is—

1. In a mold-stripper, the combination of 50 the casing, the slotted plunger therein, the gravity-hooks, and the operating lever-arms, substantially as described.

2. In a mold-stripper, the combination of 55 the casing having a slot in the upper part, the slotted plunger, the operating lever-arms, the gravity-hooks, and the wedge-block, substantially as described.

3. In a mold-stripper, the combination of 60 the casing having a slot in the upper part thereof, the hooks at the end of the casing, the slotted plunger mounted to have movement in said casing, the operating lever-arms suspended at their upper ends from a vertically-movable support, and the wedge-block suspended between the arms, substantially as described. 65

4. In a mold-stripper, the combination of 70 the casing having a slot through the upper part thereof and gravity-hooks adjacent to the lower end, the plunger within the casing having a slot therethrough with a lower A-shaped wall, lever-arms having inner enlarged eccentrically-mounted ends adapted to work past each other and having upper inner straight 75 edges to form a V when united, and a suspended wedge between the upper part of said arms, substantially as described.

In testimony whereof I affix my signature in presence of two witnesses.

WILLIAM HAZEL ADAMS.

Witnesses:

PETER SMITH,
JAMES BOURN.
